UNITED STATES PATENT OFFICE

EDWIN G. WEISSMAN, OF EASTON, PENNSYLVANIA, ASSIGNOR TO INDIVIDUAL DRINKING CUP COMPANY, INC., OF EASTON, PENNSYLVANIA, A CORPORATION OF PENNSYLVANIA.

DISPENSING DEVICE

Application filed December 19, 1928. Serial No. 327,183.

My invention relates to new and useful improvements in dispensing devices and more particularly to means for dispensing receptacles or similar articles such as paper cups or the like and has for its principal object the provision of a device which is simple and relatively inexpensive in construction, which may be easily secured in position, and which may be filled through the same opening 5 through which the articles are dispensed, in the case of cups or the like they being positioned with their closed ends uppermost and adapted to be withdrawn from the top, against the action of retaining members, a portion projecting in position to be grasped 10 by the person, desiring to obtain one.

Another object of the invention resides in the provision of a dispensing device having a follower which supports a stack of articles 20 in such a manner that they are normally urged towards the dispensing opening, means engaging the outermost article to normally retard movement of the follower, with the stack of articles, but enabling the easy withdrawal of the outermost article and the movement of the follower to position the next article in engagement with the retarding or restraining members.

Another object of the invention consists in forming the follower in such a manner that it has a portion to be received in the open end of the innermost article, and providing means for guiding the movement of the follower, a weight being 30 connected to the follower for normally urging the same towards the dispensing opening.

Still another object resides in so forming the dispenser as to provide a magazine to receive a stack of the articles and to maintain the same in a sanitary condition.

With the above and other objects in view, which will appear as the description proceeds, my invention consists in the novel details of 45 construction and arrangement of parts, described in the following specification and illustrated in the accompanying drawings, and while I have illustrated and described the preferred embodiments of the invention, it 50 will be understood that such changes may be

made as will fall within the scope of the appended claims.

In the drawings:—

Fig. 1 is a side elevation.

55

Fig. 2 is a front elevation.

Fig. 3 is a vertical section on the line 3—3 of Fig. 2 looking in the direction of the arrows.

Fig. 4 is a horizontal section on the line 4—4 of Fig. 3 looking in the direction of the 60 arrows; and

Fig. 5 is a horizontal section on the line 5—5 of Fig. 3, looking in the direction of the arrows.

In the drawings 1 indicates a top plate or casting adapted to be secured to a counter, table, or other support 2 by means of the screws 3 or other suitable fastener, and provided with a dispensing opening 4 beveled 65 interiorly, at the upper end, as shown at 5 and beveled interiorly at the bottom edge as shown at 6. The plate or casting, adjacent the dispensing opening 4, is provided with a recess 7 in which is positioned a projection 8 forming a bearing for the screw 9 which forms in turn a bearing for the pulley 10. Interiorly threaded projections 11 are formed exteriorly 70 of the plate or casting 1, around the dispensing opening 4, and openings 12 lead from the threaded bore of the projections to the interior of the dispensing openings 4. Received in each of the threaded bores 11 are the pins 13 each having an enlarged pointed head 14 formed on the inner end and adapted to extend through the opening 12 and to project interiorly of the dispensing opening 4 as 75 shown more particularly in Figs. 3 and 4 of the drawings.

At 15 I have shown a bottom plate or casting having the upwardly extending flange 16 formed around the outer edge thereof and positioned between the top plate or casting 1 and the bottom plate or casting 15, is a casting or housing 17 of the shape shown more 80 particularly in Fig. 5 of the drawings, the forward face being preferably rounded as shown at 18 and the rear being open and provided with outwardly extending flanges 19 forming a guide for the removable back plate 20 the vertical edges of which are 85 90 95 100

curved, or bent, as shown more particularly in Fig. 5 of the drawings to receive the flanges 19. The casing or housing 17 is secured to the top plate or casting 1 by means of the screws 21 or other suitable fasteners and to the bottom plate or casting 15 by means of the screws or fastenings 22. The removable back plate 20, is secured to the top plate or casting 1 by means of the screws 10 or fastenings 23 and to the bottom plate or casting 15 by means of the screws or other fastenings 24. The back plate 20 is removable, preferably by sliding downwardly and the upper movement thereof is limited by 15 means of the rib 25 formed on the plate or casting 1.

Positioned within the casing or housing 17, and held between the top plate or casting 1 and the bottom plate or casting 15 is a cylinder 26 forming a magazine for a stack of the articles 27, in the present instance the articles being shown in the shape of paper cups or containers having a tapered body portion and an exteriorly extending flange 28 around the open end. The cylinder 26 is positioned in the forwardmost part of the casing or housing 17, as shown more particularly in Fig. 5 of the drawings, and the curvature thereof conforms to the curvature of 30 the rounded portion 18 of the casing or housing. An elongated opening 29 is formed in the cylinder 26, as more particularly shown in Figs. 3 and 5 of the drawings, and forms a guide for the arm 30 which is formed on or 35 carried by the sleeve 31 which is slidably mounted on the vertically extending rod 32 positioned within the casing or housing 17 and secured therein by means of the top and bottom castings or plates 1 and 15, the upper 40 end of the rod being received in a recess in a lug or projection 23 and the lower end thereof being received in the recess of a lug or projection 34, the lug or projection 33 being formed on the plate or casting 1 and the lug 45 or projection 34 formed on the bottom plate or casting 15. Secured to that end of the arm 30, which projects through the opening 29 into the cylinder 26, by the screw 35 or other similar fastening, is the member 36 50 forming a head to support the cups 27 which are arranged in a nested stack, the head 36 being formed with an upwardly extending flange or projection 37 which is adapted to be received in the open end of the lowermost 55 cup, the edge of the lowermost cup resting upon the portion 39 extending around the flange. It will be seen that the cylinder 26 forms a magazine for the stack of cups and the arm 30 with the sleeve 31 and head 36 60 form a follower for supporting the stack of cups and normally urging them towards the dispensing opening 4 by means to be later described. The pointed heads 14 of the pins 13 engage the flange 28 of the uppermost cup 65 and the pins with their enlarged heads are

normally forced inwardly towards the dispensing opening by means of the coiled springs 39, an exteriorly threaded plug 40 being received in the threaded bore of each of the projections 11 and engaging the outer 70 end of the coiled spring to position the same. The heads or projections 14 being engaged by the coiled springs have "floating" action, and might be referred to as floating projections adapted to engage the flanges of the 75 cups. By this arrangement when a cup is to be withdrawn little exertion is needed to force the projections inwardly against the action of the coiled springs to release them from the flange of the cup. 80

Secured to the sleeve 31, by means of the screws or other suitable fastenings 41, is one end of a chain 42 the opposite end of the chain being secured, by means of a pin 43, in the recess 44 formed in the upper end of a weight 45. As shown more particularly in Figs. 3 and 4 of the drawings the chain passes over the pulley 10. Surrounding the lower end of the chain 42 and supported on the upper end of the weight 45 is a coiled 90 spring 46 which acts as a buffer when the weight is raised and engages the bottom surface of the top plate or casting 1 to prevent jar. It will be noted that the chain 42 passes through an opening 47, formed in the bottom of the top plate or casting 1. A coiled spring 48 surrounds the lower end of the rod 32 and is supported on top of the projection 34 to form a buffer for the sleeve 31 when the same is lowered. A coiled spring 49 surrounds the rod 32 and is supported by the upper end of the sleeve 31 to form a buffer for the sleeve when the same is raised to its uppermost position. Secured to the top of the bottom plate or casting 15, by means of the screw 50 or other suitable fastening is the rubber buffer block 51 adapted to be engaged by the weight 45 when the same is lowered to prevent undue shock or jar. 100

From the above detailed description it is 110 thought that the manner of using my improved form of dispensing device will be clearly understood. It will be seen that the cups or other articles will be arranged in stack formation and, if the articles are in 115 the form of cups, will be nested as shown more particularly in Fig. 3 of the drawings with the open end of the lowermost cup resting on the portion 38 of the follower head 36 and surrounding the upwardly extending 120 flange 37. The closed end or bottom of the uppermost cup will project beyond the top of the dispensing opening 4 with the flange 28 surrounding the open end engaged by the spring pressed pointed projections 14. The 125 follower is urged upwardly towards the dispensing opening by means of the weight 45 which is connected by means of the chain 42 with the sleeve 31 of the follower. The pressure behind the pointed projections 14 will be 130

sufficient to normally restrain the movement of the follower but when it is desired to remove a cup the projected portion thereof may be grasped and then by pulling upwardly the flange thereof will be disengaged from the spring controlled pointed projections 14 to release the cup and to allow its easy removal. The pointed projections will then engage the flange of the next cup in the stack, it being understood that the weight 45 will cause the follower to raise or advance a sufficient distance so that the flange of the cup will engage the projections. The weight is sufficient to normally raise the follower with the stack of cups thereon but is not sufficient to overcome the spring pressure behind the pointed projections 14 to force these cups beyond the projections. In other words the spring pressure behind the pointed projections is sufficient to overcome the raising action of the weight and allow the cups to remain stationary until removed by the person. The pointed projections, being of a "floating" character may be easily removed to release the cup when the same is withdrawn from the stack. It will be noted that the dispensing opening 4 is of a diameter substantially the same as the largest diameter of the cups and the inclined portion 6 guides the cups as they are forced upwardly into the dispensing opening. When it is desired to replenish the cups in the stack a supply thereof is passed through the dispensing opening being guided thereto by the incline 5, it being understood that the cups are introduced in inverted position so that the open end of the lowermost cup being introduced will telescope over the bottom or closed end of the cup remaining in the stack within the magazine if there be one left in position. If there are no cups left in the stack the lowermost cup will rest upon the head of the follower as has been previously described. In introducing the new supply of cups the follower will be forced downwardly against the action of the weight. The stack of cups, as can be seen, will be positioned within the cylinder 26 so as to be maintained in a sanitary condition at all times and as the cups are maintained in the stack in inverted position there is no possibility of dirt or other impurities entering the open ends of the cups. I have found an apparatus or dispensing device of the character described and disclosed as of advantage for securing quick service for it can be appreciated that a person desiring the cup may very easily grasp the bottom end of the cup, which is projecting upwardly through the dispensing opening, and then withdraw the uppermost cup through the dispensing opening and invert the same to receive the desired liquid or other commodity. I also lay particular advantage on the fact that the dispensing device may be filled or replenished through the same opening

through which they are dispensed and to fill or replenish it is not necessary to remove any parts, the pointed projections 14 being forced rearwardly due to the pressure applied in pushing the stack of cups or other articles through the filling opening. 70

Having fully described my invention what I claim as new and desire to secure by Letters Patent is:—

1. A dispensing device including a casting having an opening through which articles are adapted to be inserted or dispensed and a recess adjacent the opening, a casing secured to the casting and depending therefrom, a magazine positioned in the casing in alignment with the opening for receiving articles inserted through the opening, a follower operable in the magazine and supporting the articles therein, a pulley mounted in the recess of the casting, and means connected to the follower and operable over the pulley for normally urging the follower with the articles supported thereby towards the opening in the casting. 75

2. In a dispensing device adapted to support a stack of articles in inverted position with a portion of the terminal article exposed in position to be readily grasped, a casing having an opening through which the articles are inserted and dispensed, readily yieldable floating projections positioned intermediate the ends of the opening and extending into the opening at right angles to the vertical center of the opening, the projections normally engaging the terminal article, and means for normally urging the stack upwardly with the terminal article engaged with the projections, said projections having sufficient resistance to prevent ejection of the terminal article by the upwardly urging means but allowing the same to be withdrawn by an upward pull, the projections yielding as the articles are inserted through the opening and forced downwardly under pressure. 90

3. In a dispensing device adapted to support a stack of flanged articles in inverted position with a portion of the terminal article exposed in position to be readily grasped, a casing having an opening through which the articles are inserted and dispensed, readily yieldable floating projections positioned intermediate the ends of the opening and extending into the opening at right angles to the vertical center of the opening to normally engage the flange of the terminal article, and means for normally urging the stack upwardly with the flange of the terminal article engaged with the projections, said projections having sufficient resistance to prevent ejection of the terminal article by the upwardly urging means but allowing the same to be withdrawn by an upward pull, the projections yielding as the articles are in- 105 115 120 125 130

serted through the opening and forced downwardly under pressure.

4. In a dispensing device adapted to support a stack of articles in inverted position
5. with a portion of the terminal article exposed in position to be readily grasped, a casing having an opening through which the articles are inserted and dispensed, readily yieldable projections positioned intermediate
- 10 the ends of the opening and extending therein to normally engage the terminal article, the ends of the opening on opposite sides of the projections being formed to guide the articles into the opening when being inserted
- 15 or dispensed, and means for normally urging the stack upwardly with the terminal article engaged with the projections, said projections having sufficient resistance to prevent ejection of the terminal article by the upwardly urging means but allowing the same to be withdrawn by an upward pull, the projections yielding as the articles are inserted through the opening and forced downwardly under pressure.
- 20 25 In testimony whereof I hereunto affix my signature.

EDWIN G. WEISSMAN.
